CLAIM

We claim the ornamental design for a bezel for rack-mounted device, as shown and described.

DESCRIPTION

FIG. 1 is a perspective view of a bezel coupled to a rack-mounted device;

FIG. 2 is a front elevational view thereof;

FIG. 3 is a top plan view thereof, the bottom plan view being a mirror image of the top plan view shown;

FIG. 4 is a right side elevational view thereof, the left side elevational view being a mirror image of the left side elevational view shown;

FIG. 5 is a sectional view of the bezel taken along line 5-5 of FIG. 2; and,

FIG. 6 is an enlarged view of the bezel taken along line 6-6 of FIG. 5.

The ornamental design which is claimed is shown in solid lines in the drawings. The broken lines in the drawings are for illustrative purposes only and form no part of the claimed design.
